Attorney.

UNITED STATES PATENT OFFICE.

DAN L. HARMON, OF INDIANAPOLIS, INDIANA.

MEANS FOR SINKING WELLS.

Application filed September 11, 1924. Serial No. 737,047.

This invention relates to the sinking of wells wherein an outer casing is put down to a water bearing sand and thereupon an inner casing of such smaller diameter as to leave a considerable annular space between the two casings is lowered within the first casing down to the said sand; and wherein the inner casing terminates at its lower end with a shoe expanding downwardly and outwardly to a thin annular cutting edge at its bottom, of a diameter slightly less than that of the bore of the outer casing. The space above the shoe around the inner casing has heretofore been filled with coarse gravel or crushed stone as the work progresses that bears upon the downwardly and outwardly oblique outer face of the shoe to aid by its weight in forcing the shoe into the sand and more particularly to keep the unsupported walls of the well in the sand from caving and to keep the sand from being drawn into the inner casing through the bottom and through the walls of the casing, the walls of the lower sections of which are perforated to allow the water to pass. The sand enclosed by the cutting edge of the shoe is loosened and removed by the suction of a pump exerting its action through the inner casing.

The shoes as heretofore proposed and used, have outwardly and downwardly sloping outside faces, parallel with the inner ones, and are relatively thin at their cutting edges. Consequently the cylinder of gravel supported on the sloping top of a shoe slides downwardly and outwardly by its own weight, off of the shoe, and under the cutting edge of the latter to retard penetrative action of the shoe, and when one side of the shoe edge strikes a boulder in the sand strata as frequently happens the remainder of its cutting edge is quickly undermined by the pump suction drawing in the sand, and the sand is replaced by the gravel which forms a pack under the shoe difficult to pass and to remove. In addition, the shoe is forced to one side of the boulder and the concentric relation of the two casings is lost.

The object of my invention is first, to maintain the bottom of the cylinder column of gravel so far above and away from the cutting edge of the shoe that it cannot reach the cutting edge or be drawn into the shoe.

A second object is to provide a cylindrical surface between the cutting edge and said remote gravel support on the shoe, of suffi-

cient vertical bearing against the sand-walls of the well to prevent lateral displacement of the shoe and thereby to keep the well casings concentric.

A third object is so to support the cylinder column of gravel that the weight of the column will be deflected inwardly or toward the inner casing instead of outwardly, as heretofore, thereby eliminating the tendency of the gravel to slide down under the cutting edge of the shoe, and to drag the said walls of the well down with it and to present the lines of force on the shoe in such a manner as to get the maximum benefit of the weight of the column of gravel in sinking the well.

My further object is so to strengthen the shoe that the weight of the column of gravel will not crush and collapse it, and to improve the shoe and casing in other respects such as will hereinafter be specifically described and claimed.

In the accompanying drawing—

Fig. 1, is a vertical section of a well illustrating my invention and showing the inner casing in elevation and the lower portion of said inner casing and a portion of the shoe in vertical section.

Fig. 2, is a cross section of the inner casing on the line 2—2 of Fig. 1, looking downwardly, and Fig. 3, is a modification showing the inner casing and shoe in vertical section.

Like characters of reference indicate like parts in the several views of the drawing.

Referring to Fig. 1 of the drawing, an outer casing 4 of usual tubular construction is sunk to the level 3 in the top of the strata of water-bearing sand 5, by the usual methods, which leaves the casing interior empty and open.

The inner casing is also of tubular construction. Its bottom sections 8 have wall perforations 7, as shown, for the free admission of water to the interior of the casing. The inner casing sections 6 have unperforated walls. The sections 6 and 8 are joined together by external bands 9, here shown as riveted, but they may be threaded and screwed together at the joints. The sections are assembled a section at a time as the depth of the well increases.

Attached to the lower end of the lowest section 8, of the casing, is a shoe 10, preferably of cast metal, having a cylindrical inner wall 11 of the same diameter as the inner wall of section 8, but off-set at its

upper portion to form a shoulder and seat for the lower end of the inner casing and to let the inner wall of section 8 in flush with the inner cylindrical wall 11 of the shoe. 5 Below the wall 11 the inner wall 12 of the shoe flares downwardly and outwardly and terminates with a relatively sharp earth-cutting circular edge 13, approximating the internal diameter of the outer casing 4, 10 through which outer casing the shoe is lowered to the water-bearing sand strata 5. The outer wall 14, of the shoe, is cylindrical or as nearly cylindrical as it can be to avoid clogging in the sinking of the shoe and 15 inner casing into the sand strata 5. The outer wall 14 preferably terminates opposite the lower end of the bottom section 8, but this may vary considerably either way, without departing from the spirit of my invention. 20

The top of the shoe, outside of the seat for casing 8, is formed with an annular depression 15, preferably V-shape in cross-section which is the seat and base-support for a 25 column of coarse granular material 16, of gravel or crushed stone filling the space between the inner and outer casings as far as the outer one extends and of the unsupported walls of the well below that. The material 30 16, is introduced at the top as soon as the inner casing and shoe are placed in the well and its space is kept full thereafter.

This coarse granular material 16 keeps the fine sand of the water bearing strata 35 from caving in and from being drawn into the inner casing with the water by pump suction. It also provides much of the weight or driving force required to sink the shoe and inner casing in the water bearing 40 sand the desired distance. The oblique outer wall 17, of the depression 15, in the top of the shoe, throws the weight of the column inwardly against the shoe in such manner as to secure the maximum benefit of its weight 45 in sinking the well and obviates the tendency to break down the sand walls of the well and crowd under the cutting edge of the shoe, as in those shoe forms wherein the outer wall of the shoe is substantially parallel with its 50 inner wall.

My above described shoe construction, moreover, presents a high, substantially cylindrical, wall to contact with the undisturbed newly made wall of the well, and 55 thereby prevents the lateral displacement of the foot and inner casing. It further, provides a solid mass of metal in the shoe midway of its height which strengthens the shoe against collapse from the weight on it and 60 from the force applied to sink it, and its attached inner casing.

In the modification shown in Fig. 3 the shoe is formed out of sheet metal, bent to the same outer and inner faces and riveted together. The oblique member 17' forms 65 the outer side of the V-shape channel and a reinforcement to strengthen the shoe.

The end of casing section 8' rests upon the edge of the inner plate of the shoe and the two are retained by an outer band 9² having 70 a lower outwardly flared portion.

While I have here shown and described the best embodiment of my invention now known to me, it is capable of modifications, some of which I have herein specifically referred to, and others are possible without departing from the spirit of my invention. I therefore desire to include all variations which come within the scope of the appended 75 claims. 80

I claim:—

1. In an appliance for sinking wells, the combination of a sheet-metal casing with a shoe secured to said casing and flaring outwardly and downwardly internally therefrom and terminating in a lower relatively sharp earth cutting edge, said shoe having a substantially cylindrical outer side above said earth-cutting edge and merging with a top portion connecting it with said flaring first side, said top portion having a channel extending around the casing, the walls of more or less of the casing next to the shoe being perforated and an outer casing of 90 sufficiently greater inside diameter than the outside diameter of the shoe through which the shoe and its attached casing are inserted. 95

2. In an appliance for sinking wells, the combination with a sheet metal casing having perforated walls for a suitable distance beginning at one end, of a one piece shoe 100 secured to the perforated end of said casing said shoe flaring outwardly and downwardly internally from the end of the casing and terminating in a lower relatively sharp earth cutting edge and having a substantially cylindrical outer side extending from the earth-cutting edge and terminating approximately 105 opposite the perforated end of the casing, and a member connecting the inner and outer upper walls of the shoe, said connecting member having a channel extending around the casing which channel is angular in cross section with an inwardly downwardly sloping outer side, and an outside casing in 110 which the first casing and its attached shoe are inserted with a sliding fit between the shoe and the outer casing. 115

Signed at Indianapolis, county of Marion, State of Indiana, this the 4th day of September, 1924.

DAN L. HARMON.
